TUBE BENDING MACHINE WITH MECHANISM FOR CONTROL OF WALL THICKNESS ACTUATED BY THE ROTATABLE BENDING DIE IN ACCORDANCE WITH ITS SPEED OF ROTATION

Bryon F. Bower, Aurora, Ill., assignor to Pines Engineering Co., Inc., Aurora, Ill., a corporation of Illinois

Application April 7, 1954, Serial No. 421,506

8 Claims. (Cl. 153—40)

The present invention relates to tube bending machines and is more particularly directed to means for improving the bending operation so as to make it possible even in relatively thin walled tubing to substantially maintain the original wall thickness in the outer walls of the bends.

In the bending of tubing in accordance with my invention the tubing is usually bent around a bending die, a clamp block being used to hold the advancing end of the tubing against the bending die. In addition, a pressure die presses the tube snugly against the bending die. Preferably, a mandrel is placed inside the tube and is advanced to the proper position for bending, which is with its rounded tip at the tangent line of bend. Bending takes place when the clamp block and bending die start to turn about the axis of the bending die. When properly positioned, the mandrel does not advance after the bending die is under way.

As the bending die is rotated, the tube is drawn along with it and the pressure die does the actual bending of the tube against the approaching surface of the bending die.

It will be appreciated that in a bending operation of this type the wall of the tube on the outside of the bend is subjected to a terrific tension and this tension increases as the radius of the bend is made smaller. Not only is the outer wall subjected to bending stresses but also to the force necessary to pull the tubing around the bending die. As a result, the tubing is weakened by a stretching or thinning of the outer wall with an increased possibility of failures.

It is an important object of the present invention to provide an improved tube bending means whereby the wall thickness of the tube is substantially maintained throughout the outer wall of the bend or is reduced to a desired predetermined thickness.

Another object of this invention is to provide tube bending means whereby the thickness of metal in the tubing wall is controlled and a better all around strength is obtained in the bent portion of the tubing.

In my Patent No. 2,357,873, issued September 12, 1944, means are provided for pushing the tubing as it is being drawn by the bending die so as to relieve the tubing itself of a substantial portion of the strain necessary to draw the tubing around the die. This pushing of the tubing is carried out in such a fashion as to eliminate the drag of the tubing so that the principal strain placed on the tubing is that necessary to bend it. This means, of course, that the metal in the outer half of the tubing bend will be stretched to the amount necessary to provide the additional length at the outside of the bend. Although this avoids some of the reduction in cross-section of the tubing wall, there still exists a weakening of the metal at the bend thereby making it the weakest portion of the finished tubing. This is true in the operation of all bending machines of the same type.

Normally when a tube is bent over a bending die, the tube travels toward the die at a speed approximately

2

equivalent to the speed at which the bend is formed at its centerline, commonly known as its neutral axis. When bending occurs, the inside wall of the bend is formed at a speed lower than at either the neutral axis or the outside wall, the speeds being in direct proportion to the respective radii at the bend. It follows that a thickening of the inside wall of the bend and a thinning of the outside wall thereof are also in direct proportion to their respective radii. Accordingly, if the travel of the tube toward the bending die is increased to equal the forming of the bend at the outside wall, the original thickness of the tube will be maintained substantially along the outer wall of the bend.

In my present invention, there is provided means for so controlling the pushing pressure applied to the tube as to effect a rate of travel necessary in maintaining the thickness of the outer wall of the bend. This control feature is accomplished through a valve so connected operatively to the bending mechanism as to translate rotary movement of the bending die into pushing pressure required on the tube.

Other and more detailed objects and advantages of the invention will appear more fully in the following description, reference being made to the accompanying drawings in which preferred forms of the invention are shown. It is to be understood, however, that the drawings and the description are illustrative only and the invention disclosed therein is limited only by the claims.

In the drawings:

Figure 1 is a plan view of a tube bending machine embodying my invention;

Figure 2 is a side view in elevation of the bending machine shown in Figure 1;

Figure 3 is an enlarged fragmentary vertical cross-sectional view taken along the line 3—3 of Figure 1 and illustrating details of construction of a pressure die roller, a bending die, and associated mechanism;

Figure 4 is an enlarged end view in elevation of the machine showing the relation of parts with the clamping die in an open position;

Figure 5 is an enlarged fragmentary vertical cross-sectional view, taken along the line 5—5 of Figure 4, showing details of construction of certain of the relatively movable parts of the clamping die mechanism;

Figure 6 is a view, similar to Figure 4, showing the tubing in clamped position;

Figure 7 is an enlarged plan view in elevation, embodying certain elements of the die mechanisms, illustrating a completed bending operation and the relative position of the mandrel;

Figure 8 is a diagrammatic view illustrating the control apparatus by which the several operations are carried out in a tube bending operation;

Figure 9 is an enlarged vertical cross-sectional view in elevation of the directional valve, with parts in neutral position, shown in Figure 8;

Figure 10 is a fragmentary cross-sectional view, with parts in elevation, showing details of construction of the actuating handle connection to the spool of the directional valve of Figure 9;

Figure 18 is a view diagrammatically illustrating a modified form of bending control mechanism;

Figure 19 is a side view in elevation of the tube gripping member of the pressure die shown in Figure 18;

Figure 20 is a front view in elevation of the tube gripping member showing the serrated gripping face; and,

Figure 21 is a view diagrammatically illustrating a second modified form of bending control mechanism.

Referring now in detail to the drawings, my invention is shown as embodied in a tube bending machine wherein the numeral 30 represents the base of the machine and the numeral 31 is the frame thereof. At one end of the frame 31 there is mounted for rotation a bending die supporting head 32 upon which a bending die 33 is removably mounted. The supporting head also carries with it a frame work 34 that supports a clamping die mechanism 35 for clamping the end of a piece of tubing to the bending die 33. The framework 34 also supports an operating cylinder 36 that is adapted to close the clamping die mechanism 35 against the corresponding portion of the bending die.

As best shown in Figure 5, the frame 34 has a guide 37 for slidably receiving therein a clamping die actuator 38. An inverted T-slot 39 in the upper side extends along the actuator and terminates short of the outer end thereof in which an adjusting screw 40 is threaded. An adjusting block 41 has depending from its forward end a slide portion 42 seated within the slot 39 and engaged by the screw 40. A spacer block 43, inserted between the adjusting block 41 and a clamping die 44, is of a length to properly position the die at a predetermined distance from the bending die 33 when in an open position as shown in Figure 4. A spacer of shorter or longer length may be inserted to accommodate tubing of a diameter different than shown. The necessary adjustment of the die 44 to insure closing on an inserted length of tubing 45 (Figure 6) is effected through the screw 40. When adjusted, the block 43 and the die 44 are clamped to the actuator 38 by means of clamp bolts 46, 46 each of which have a head 47 slidable within the slot 39 and a nut 48 for locking the bolt in place.

A pressure die mechanism 49 guides the forward movement of the tubing and cooperates with the bending die 33 to bend the tubing as the die is rotated. A frame 50, carried by the machine frame 31 and having spaced side members 51 and 52, has a guide 53 for slidably receiving therein a pressure die actuator 54. An adjusting screw 55 permits adjustment of a roller support 56 in the guide to position rollers 57, 58 and 59 in tube engaging positions. When adjusted, the support is locked by clamp bolts 60, 60 to the actuator 54 in a manner similar to the locking of the clamp bolts 46, 46. Each of the rollers has a circumferentially extending semi-circular tube receiving slot, similar to a slot 61 in the roller 57. As shown in Figure 3, the roller support 56 is bifurcated at its forward end to provide upper and lower plates 62 and 63 between which the rollers are carried by mounting pins, only pin 64 being shown for roller 57. It will be noted that roller 57 is positioned in diametric alignment with the rounded end of bending die 33 for a purpose to be more fully defined herein-

after. The rollers 58 and 59, spaced laterally of the roller 57, engage and freely guide the tubing 45 in its forward movement during the bending operation. The pressure die mechanism is adapted, when properly adjusted, to move the rollers into and out of engagement with the tubing by means of a cylinder 65 having a piston rod 66 connected by a set of links and pins indicated generally at 67 in Figure 2. The cylinder 65, as well as the cylinder 36 which operates the clamping die mechanism 35, is supplied with a suitable fluid under pressure (either liquid or air). The details of the control of this mechanism form no part of this invention and therefor such details have not been shown.

Tubing to be bent is placed over a mandrel 68 that has its end rounded as indicated at 69 (see Figure 7). This mandrel is supported upon a mandrel actuating rod 70 which is threaded into the mandrel as indicated at 71. A number of types of mandrel mountings may be employed one of which is shown in my Patent No. 2,357,873. In the arrangement therein, provision is made for an operating cylinder and a piston connected to the mandrel actuating rod. The actuating rod is of such length that, when the piston is advanced, the rounded tip 69 of the mandrel is at the proper position for bending the tube which is in diametric alignment with the rounded end of the bending die 33 and the pressure die roller 57. As the details of the actuating rod and the mechanism for its advancement form no part of this invention, they have not been shown.

The normal operation of a bending machine, such as has just been described comprises a sequence of operations as follows: first, the tubing 45 is placed over the mandrel and set into a tube receiving groove 72 of the bending die 33. The clamping die 44 is next caused to close with its tube receiving groove 73 against the tubing to clamp the same against the bending die. Actuation of the clamping die is effected through the operating cylinder 36 from which extends a piston rod 74 connected to the clamping die actuator 38 by means of a set of links and pins generally indicated at 75 and which extend between the side members 76 and 77 of the frame 34. The mandrel is then advanced to the proper position. Also, the pressure die mechanism is closed into position against the tubing. Next, the bending die is started to rotate with a shaft 78 that extends vertically down through the frame (Figure 4). The bending die and the clamping die mechanism 35, as they rotate with the shaft, pull the tubing around the axis of the bending die. The rollers 57, 58 and 59 prevent the rearwardly extending part of the tubing from swinging so that the tubing actually is bent by the roller 57. The tubing 45, as it is drawn around the bending die, is subjected to a terrific strain, particularly at the point where it is being bent and pulled around the nose of the mandrel. The rounded mandrel nose is necessary to prevent the tube from flattening under this strain in order to reduce the distance around the curve and thus reduce the amount that the metal must stretch.

It has been found that the strain placed on the tubing not only weakens the metal but practically limits the sharpness of the bend that can be given to tubing by drawing it around a bending die. However, I have developed mechanism whereby it is possible not only to eliminate practically all of the strain to which the tubing is subjected and thus get sharper bends by means of a bending die operated in the manner previously described, but also to maintain substantially the thickness of the unbent tubing around the outside of the bend thereby retaining all of the original strength of the tubing.

In accordance with the principles of the present invention, the tubing is pushed forward toward the bending die as it is being drawn thereby so as to relieve the tubing itself of the strain necessary to draw the tubing around the die. This pushing of the tubing is carried out at that pressure necessary to eliminate both the strain of draw-

ing the tubing and the stretching thereof to provide the additional length at the outside of the bend.

It has been determined during the bending operation that the yield point of the metal in the tubing is exceeded in a small working area adjacent to the tangent line of contact between the tubing and the rounded nose of the bending die or, stated in another way, the line of contact at the diametrical axes of the rounded nose of the bending die and the adjacent roller 57. With metal in a fluid state within the small working area, any pressure exerted axially lengthwise of the tubing will be effective at and confined to that working area. Consequently, the rounded nose of the mandrel need only to prevent a collapse of the fluid metal rather than to resist a drawing strain. Also, because fluidity of the metal is confined to such a small working area, the pressure exerted axially on the tube, if controlled, will not effect a forward bending at the tangent of the bend. In Figure 17, the narrow working area is identified by the numeral 79.

As shown, the distance from point A (intersection of the neutral axis of the tubing with the aligned diametrical axes of the bending die 33 and the pressure die roller 57 at the end of the bend) to point B (intersection of the neutral axis of the tubing with the diametrical axes of the bending die 33 at the start of the bend) is shown by the line of normal travel D—E on the rearward straight section of the tubing. During this travel in the normal bending of a tube, the length along the inside of the bend is less than along the neutral axis and the length along the outside of the bend is greater than along the neutral axis. As a result, the wall on the inside of the tubing bend is subjected to compression and the thickness increases while the wall on the outside of the tubing bend is subjected to tension and the thickness decreases. The difference in length along the neutral axis and along the outside of the tubing bend is identified by the distance E—C. If sufficient pressure is exerted at P in a direction axially lengthwise of the tubing to effect a movement of the tubing from D to C instead of from D to E during the complete bending operation, then sufficient metal will be available at the working area 79 to avoid a stretching or thinning of the wall thickness along the outside of the tubing bend. This has the apparent mathematical effect of moving the neutral axis from the center of the tubing to the outside thereof. Clearly, by increasing both the compression on the inside wall of the tubing bend and its thickness, the strength of the tubing will be enhanced at that area. Similarly, by eliminating both the stretching of the outside wall of the tubing bend and a reduction of its thickness, the original strength of the tubing will be maintained at that area.

In the bending of tubing without pressure being exerted in a direction axially lengthwise of the tubing toward the bending die, the following proportions determine the thickness of the inside and the outside walls of the bend.

$$\frac{T}{T_1} = \frac{R_1}{R}$$

T =wall thickness of unbent tubing

T_1 =thickness of outside wall of bend

R =radius of neutral axis at bend

R_1 =radius of outside wall of bend

$$\frac{T}{T_2} = \frac{R_2}{R}$$

T_2 =thickness of inside wall of bend

R_2 =radius of bending die groove and inside wall of bend.

Assuming that tubing 45 is 2 inches in diameter, that the radius of the tube receiving groove on the rounded nose of the bending die is 1", and that the wall thickness of the unbent tubing is .10", then from the foregoing—

$$\frac{.10}{T_1} = \frac{3}{2}$$

$$3T_1 = .20$$

$T_1 = .0667"$ —the outside wall has been reduced .033" in thickness or 33 1/3%.

Or—

$$\frac{.10}{T_2} = \frac{1}{2}$$

$T_2 = .20"$ —the inside wall has doubled in thickness.

However, if the neutral axis is mathematically assumed to coincide with the center line of the outside wall because the required pressure has been exerted on and axially lengthwise of the tubing, then R and R_1 will both be equal, or—

$$\frac{.10}{T_1} = \frac{3}{3}$$

$$3T_1 = .30$$

$T_1 = .10"$ —and the thickness of the unbent tubing has been maintained in the outside wall of the bend.

At the same time—

$$\frac{.10}{T_2} = \frac{1}{3}$$

$T_2 = .30"$ —or the thickness of the inside wall of the bend has been trebled.

Accordingly, there is provided herein mechanism by which to effect the movement of the neutral axis of the tubing to the outside wall of the bend and to exert pressure against the tubing to move the tubing to the bending die a distance equal to the length of the outside wall of the bend.

In Figure 3, the bending die 33 is shown as being provided with an upwardly extending boss 80 having a reduced end 81 for mounting a control drum 82. A nut 83, on the end of shaft 78 extending through the assembly, serves to hold the shaft in a depending position. The drum and the bending die co-rotate on a common axis for a purpose to be more fully explained later.

It is to be noted that the periphery of the drum is in alignment with the outer wall of the tubing 45 when seated in the bending die. In other words, the radius of the drum is equal to the distance from the outside of the tubing 45 to the longitudinal axis of the shaft 78 on which both the bending die 33 and the drum are mounted.

As best shown in Figures 1 and 2, a pusher cylinder base 84 is mounted on the machine frame 31 for forward or lateral adjustment. A pair of aligned pusher cylinders 85 and 86, shown in vertical relation to each other, are carried by a frame 87 mounted on the base. The cylinder 85, with a piston 88 and a forwardly extending piston rod 89, is adapted to operate when supplied with a suitable fluid under pressure. Similarly, the cylinder 86 has a piston 90 and a forwardly extending piston rod 91.

An L-shaped bracket 92, mounted on the frame 87, supports an idler drum carrier 93 by means of a stud 94. An idler drum 95, carried by the carrier 93, is operatively connected to the control drum 82 by means of an endless tape 96 applied around the drums.

Located between the pusher cylinders and the bending mechanism is a tubing clamp structure 97. A raised member 98 on the machine frame 31 carries a slideable base 99 on which there is mounted a clamp structure frame 100. Bosses 101 and 102 extend from the rear of the frame 100 and receive, respectively, the threaded connecting ends 103 and 104 of the piston rods 89 and 91. The tubing clamp structure 97, acting as a cross-head, is thereby actuated along the member 98 by the pusher cylinders.

A cylinder 105, pivotally mounted as indicated at 106 between frame side members 107 and 108, is actuated when supplied with a suitable fluid under pressure. A piston 109 has a piston rod 110 pivotally connected

through a block 111 to a wedge-shaped clamp member 112. The piston actuates the clamp member along a sloping surface 113 whereby the groove 114 in the clamp member seats against the tubing 45 inserted through the opening 115. The wedging action thereby locks the tubing in the tubing clamp structure 97.

A dove-tailed guide bar 116 on the clamp structure frame 100 has a tracer or follower valve 117 mounted for adjustment along its length. At the forward end of the valve is a tracer finger or sensing arm 118 adapted to contact a flag member 119 mounted to slide along the tape 96 and with a locking screw 120 to clamp it in adjusted position.

In Figure 4 is illustrated the mechanism through which the bending die 33 is rotated. The shaft 78 extends downwardly through the machine frame 31 and has mounting sleeves 121 and 122 locked thereon by a key 123. At the upper end of the sleeve 121 is mounted a roller bearing 124. It will be noted that the sleeve tapers downwardly to receive a chain drive sprocket 125 which is locked against relative rotation by a key 126. A pair of lock nuts 127 and 128 on the sleeve 122 are operable to adjust the sprocket vertically on the sleeve 121. Another roller bearing 129, mounted in the machine frame 31, embraces the sleeve 121. A sleeve 130 carries a support arm 131 and extends and is fastened to the side member 76 by means of bolts 132 and 133. The sleeve 130 is retained on the sleeve 121 by a lock nut 134.

Transversely spaced, parallel supports 134a project rearwardly from the end of the machine opposite the bending mechanism and extend beyond the base 30 of the machine and have a web 135a transversely connected between their lower edges. Vertically spaced, transverse supports 137 and 138 extend between the supports 134a and carry a pin 136 on which a chain idler sprocket 135 is journaled. The idler sprocket is mounted in horizontal alignment with the drive sprocket 125.

Between the sprockets and mounted on the machine frame 31, by means of hangers 139 and 140, is a bending cylinder 141. A piston 142, within the cylinder, has a forward piston rod 143 and a rear piston rod 144. A connector 145 is threaded or otherwise secured to the end of the forward piston rod and a similar connector 146 is secured to the other or rear piston rod. A roller chain 147, with the ends secured to the connectors 145 and 146, is mounted around the sprockets 125 and 135.

The cylinder is arranged to operate when supplied with a suitable fluid under pressure. The piston moves to the right (Figures 1 and 2) to effect an operation of the bending mechanism and moves to the left to return the mechanism to its original position. It will be noted that the piston rods 143 and 144 are of different diameters. As the piston rod 143 is relatively small in diameter, a maximum of piston area is exposed to fluid pressure during the bending cycle. Conversely, the piston rod 144 being of larger diameter reduces the piston area exposed to fluid pressure thereby effecting a quick return of the bending mechanism to starting position. Details of the control of the bending cylinder mechanism form no part of the present invention and therefor such details have not been shown.

Reference is now made to Figure 8 of the drawings wherein there is diagrammatically illustrated the general system of controls for the tubing clamp structure and the pusher cylinders. A motor 148, which is mounted on the under-side of the web portion 135a drives a pump 149 that draws fluid, preferably a liquid such as oil, from a reservoir 150 through a suction line 151. The fluid is then pumped through a conduit line 152 to a directional valve 153. This system is intended to operate at a predetermined pressure and when the pressure is exceeded sufficient fluid is bled through a pressure relief valve 154 and by-passed through a conduit

155 back to the reservoir to maintain the operating pressure.

Details of construction of the directional valve 153 are best shown in Figures 9 to 13 inclusive. The valve has a body 156 axially chambered as at 157 to slidably receive therein a spool 158. Both ends of the chambered body are closed by threaded plugs 159 and 160. The plug 160 is provided with an opening 161 through which extends an actuating rod 162 from the spool. 10 Valve lands 163 and 164 are intermediately spaced on the body of the spool. An abutment member 165 extends outwardly from the valve land 163 and a similar abutment member 166 connects the valve land 164 and the actuating rod 162. It will be noted that the abutment member 166 is larger in diameter than the actuating rod for a purpose to be more apparent later.

Spaced ports 167 and 168 are located at one side of the valve body 156 and are positioned intermediately relative to spaced ports 169, 170 and 171 at the opposite side of the body. With the spool 158 moved to the position shown in Figure 9, the lands 163 and 164, respectively, cover the ports 167 and 168 and are positioned intermediately of the ports 169, 170 and 171. In this relation of parts, the valve 153 is in a neutral or inoperative condition.

In order to move the spool to render the valve operative, an actuating handle mechanism 172 is provided. The free end of the actuating rod 162 is bifurcated having sides 173 and 174 between which an actuating handle 30 175 is intermediately connected by a pivot 176. At its lower end 177, the handle is bifurcated to embrace an end 178 of reduced width of a link 179 and is rockably connected thereto by a pivot 180. The opposite end 181 of the link, similar to end 178, is connected by means of a pivot 182 to and between sides 183 and 184 of a bifurcated extension 185 of the valve body 156. A ball shaped upper end 186 of the actuating handle facilitates being grasped by an operator.

Figure 12 shows the relation of parts when the actuating handle has been swung toward the valve, as shown by the arrow. It will be noted that the spool abutment member 165 is seated against the end plug 159. The resulting position of the spool locates the valve land 163 between the ports 167 and 169 and the valve land 164 between the ports 168 and 170.

Figure 13 shows the relation of parts when the actuating handle has been swung away from the valve in a direction shown by the arrow. The spool has now been moved to a position in which the abutment member 166 is seated against the end plug 160. The valve land 163 is thereby moved to a position between the ports 167 and 170 and the valve land 164 between the ports 168 and 171.

From the foregoing, it will be observed that the lands are so spaced as to be positioned either covering certain ports or located between them. Also, the abutment members on the spool, when seated against an adjacent end plug, properly position the lands in relation to the ports, as shown and described.

With a shifting of the spool 158 to the right, as in Figure 13, fluid under pressure from conduit 152 flows through the valve 153 into a conduit 187 to the clamp cylinder 105 (Figures 1 and 2) thereby advancing the piston 109 to close the wedge-shaped clamp 112 against the tubing 45 inserted through the tubing clamp structure 97. Fluid, within the cylinder ahead of the piston, flows through a conduit 188, through the directional valve 153, and through conduits 189 and 190 to the reservoir 150. Any fluid trapped within the valve between the land 164 and the end plug 160 is drained through the port 171 and a conduit 191 to the drain conduit 190. When the piston 109 is fully advanced in the cylinder 105, the pressure in conduit 152 rises until it exceeds the pressure-setting of a sequence valve 192. The sequence valve then opens

permitting fluid to flow from the pressure conduit 152 through a conduit 193 to the tracer or follower valve 117 where it is available for operating the pusher cylinders.

As shown in Figures 14, 15 and 16, the valve 117 has a body 194 chambered as at 195 to slidably receive a spool 196. The spool is provided with end guide lands 197 and 198 and intermediate valve lands 199 and 200. Unlike the valve lands previously described with the directional valve 153, the lands 199 and 200 have modified peripheral surfaces. The land 199 is provided with an intermediate cylindrical peripheral surface 201 flanked by tapered or conical shaped surfaces 202 and 203. Similarly, the land 200 has an intermediate cylindrical peripheral surface 204 flanked by tapered or conical shaped surfaces 205 and 206. The tapered surfaces are provided to effect a more gradual opening and closing of the associated port, it being desirous in the valve 117 that the actuation of spool 196 be smooth.

The chamber of the valve body is closed at one end by a threaded adjusting plug 207 and by a closure plug 208 at the other end. By threading the plug 207 within the chamber, adjustment is made in the tension of a coiled spring 209 to normally locate the spool in an offset position in which the guide land 198 is seated against the closure plug 208.

On one side of the valve body there is provided spaced ports 210 and 211 located intermediately with respect to opposed ports 212, 213 and 214. When the spool is in an offset position, as shown in Figure 14, the valve land 199 is located between ports 210 and 213 and the valve land 200 between the ports 211 and 214.

An actuating rod 215 extends from the end guide land 198 through an opening 216 in the closure plug 208. The tracing finger or sensing arm 118 is removably mounted on the end of the actuating rod and held in adjusted position by a set screw 217. Any pressure exerted against the arm 118 effects movement of the spool 196 against the coiled spring 209. The two positions to which the spool is moved, from the offset position shown in Figure 14, are illustrated in Figures 15 and 16.

In the offset position, fluid under pressure from the conduit 193 flows through the valve, the port 211, and a conduit 218 into the pusher cylinders 85 and 86. The pistons 88 and 90 are thereby forced ahead moving both the tubing clamp structure 97 and the tubing 45 clamped therein by the wedge-shaped clamp 112. Fluid from the forward or rod ends of the cylinders flows through a conduit 219, through the tracer valve 117, and into conduits 220 and 221 to return to the reservoir 150. Similarly, any fluid in the chamber between the spool lands 200 and 198 is drained to the reservoir 150 through a conduit 222. Accordingly, in its normal offset position, the valve 117 effects a forward movement of the clamped tubing 45 toward the bending die 33.

When pressure is applied to the tracer finger 118, the coiled spring 209 of the tracer valve 117 is depressed. With the valve spool 196 moved to a position shown in Figure 15, the valve lands are located over and mask the ports 210 and 211 thereby shutting off the flow of fluid to the conduits 219 and 218, respectively. The valve is then in an inoperative or neutral condition. With the parts so positioned, any fluid trapped between an end land and its adjacent valve land is drained through conduits 220 and 222.

Actually, the spool 196 of the tracer valve 117 is required to be shifted very slightly to effect the changes necessary to actuate or stop the operation of the pusher cylinders as shown in Figures 14 and 15. The system, then, is extremely sensitive and any slight deflection in the tracer finger or sensing arm 118 causes an immediate response in the pusher cylinders.

With the system in partial operation as described, that is with the clamp structure 97 clamping the inserted tubing and fluid pressure available at the tracer valve 117

to actuate the pusher cylinders 85 and 86, the bending mechanism is ready for operation.

The bending cylinder 141 is first caused to operate in a bending direction or with the piston 142 travelling to the right, as shown in Figure 1. Movement of the piston causes the driving chain 147 to start rotation of the sprocket 125 which in turn starts a rotation of the bending die 33 in a clockwise direction. In this movement, the bending die and the clamping die unit 34 start a pulling of the tubing around the axis of the bending die. Simultaneously, the control drum 82 rotates with the bending die thereby moving the endless tape 96 and the flag member 119 adjustably carried thereon.

The tracer or follower valve 117 and the adjustable flag member 119 are preset relative to each other. This is accomplished by moving the flag member along the tape and locking it at a desired position to provide a space between the flag member and the sensing arm 118. This space provides a lead for the movement of the sensing arm to the flag member before the start of the bending operation and results in placing the tubing under compression and in a preloaded condition. The amount of preloading will, of course, depend upon such factors as the size of tubing, its wall thickness, and the type of metal therein.

Should the bending cylinder not be operative, then the sensing arm engages the flag member and the pressure exerted on it forces the spool to a position as shown in Figure 15 in which the valve 117 becomes inoperative. If the bending cylinder is operative, then the control drum 82 rotates and the tape 96 draws the flag member away from the sensing arm and the valve 117 becomes operative by the parts assuming the relative positions shown in Figure 14. As soon as the tape 96 starts to move to draw the flag member 119 away from the sensing finger 118, the coiled spring 209 of the valve 117 shifts the spool forward to uncover the port 211 permitting fluid to flow through the conduit 218 and actuate the pusher cylinders 85 and 86. Accordingly, so long as the flag member moves ahead of the sensing arm the pusher cylinders will be actuated. If the bending mechanism stops, the stationary flag member causes the valve 117 to become inoperative which stops the actuation of the pusher cylinders. By this sensitive mechanism, the pushing force exerted on the tubing forcing it toward the bending die is controlled.

The operative relation of the respective mechanisms is such that sufficient pressure is developed by the pusher cylinders to effect the same increment of movement of the tubing toward the bending die as the distance traversed along the bend of the tubing at the outside thereof. This is accomplished by the control drum radius R_c being such as to locate the tape 96 at the same distance from the center of rotation of the bending die 33 as the outside surface of the bend in the tubing (see Figure 3).

As the bend proceeds, the pusher cylinders continue to force the tubing toward the bending die into the small working area tangent to the bending die. The metal in a fluid state in this area is then drawn into the outside wall 60 of the tube bend as previously described. By constantly providing sufficient metal at the outside of the bend to avoid stretching, the original wall thickness of the tubing is generally maintained throughout the length of such outside wall. Similarly, too much metal is provided at 65 the working area at the inside wall of the bend. This additional metal is evenly forced into the inside wall thereby increasing its thickness. Should the original thickness not be accurately maintained throughout the bend, the decrease would be negligible and of no consequence as the cold working of the metal during the bending operation introduces additional tensile strength in the outer wall.

Inasmuch as the mechanism described herein practically eliminates any strain on the tubing as it is being bent, limitations as to the sharpness of bends previously

experienced in tube bending machines are overcome. Also, because much less resistance is encountered in the rotation of the bending die, less clamping pressure on the tubing is required. Furthermore, the need for more than one segment in a mandrel to support the outer wall of the tube during bending is also eliminated since tension in the outer wall is reduced to a minimum. All of these features provide for easier bending particularly where the bends are close together.

When the bend is completed, operation of the bending cylinder is stopped and the spool of the directional valve 153 is shifted from the position shown in Figure 13 to that shown in Figure 12. In the resulting relation of valve parts, fluid under pressure flows from the conduit 152 to the conduit 188 and into the cylinder 105. The piston 109, in moving to the rear end of the cylinder, withdraws the wedge-shaped clamp member 112 and releases the tubing 45 in the clamp structure 97. Any fluid in the cylinder on the opposite side of the piston is drained away through the conduits 187, 191 and 190 back to the reservoir 150. Similarly, any fluid trapped between the guide land 163 and the end plug 159 is drained through the conduit 189.

As fluid again flows through the conduit 152 following a release of the static pressure required in maintaining clamp pressure on the tubing, the pressure in the line drops and the sequence valve 192 closes thereby shutting off the flow of fluid through the conduit 193 to the tracer valve 117. For lack of pressure, the valve 117 then becomes inoperative. This condition continues until the piston 109 is bottomed in the cylinder 105 at which time pressure in the conduit line 152 again builds up to exceed the setting of the sequence valve 192. When the sequence valve opens, fluid under pressure again flows through conduit 193 to the tracer valve 117. Inasmuch as the bending cycle was stopped, the flag member 119 is at rest and the abutting tracer finger has moved the spool of the tracer valve to the position shown in Figure 15 rendering it inoperative.

To reverse the tracer valve and thereby effect a reverse operation of the pistons 88 and 90 in the pusher cylinders requires a manual actuation of the tracer finger to move the spool to the position shown in Figure 16. Fluid from the pressure conduit 193 then flows through the conduit 219 to effect a reversal of the pusher mechanism and a relief of the pushing force previously applied on the tubing during the bending cycle. Fluid in the cylinders on the opposite sides of the pistons drain through conduits 218, 222 and 221 to the reservoir.

The clamp and pressure die cylinders are then actuated in a reverse direction to release the tubing from the bending die. The bent tubing is either removed to be replaced or reset at a new position for another bend. The bending cylinder is then actuated in a reverse direction to return the bending arm and the machine is again ready for a new bending cycle.

Modified forms of construction of the control mechanism are shown in Figures 18, 19, 20 and 21.

In Figure 18 is shown diagrammatically the bending die 33 and clamping die 44 having been rotated to the completed bending position. The pressure die mechanism is of the same construction previously described except that the roller support 56a, carried on the frame 56a, is sufficiently wider to carry a cylinder 225. The cylinder has a piston 226 with a piston rod 227 connected to a cross-head 228.

Interposed between the rollers 57, 58 and 59 and the tubing 45 is a pressure die 229 having a back plate portion 230, resting against the rollers, and a tube gripping portion 231. A boss 232 extends from the end of the back plate portion adjacent to the cross-head 228 and is fixedly connected thereto. The cross-head also carries the tracer valve 117 against the finger or arm 118 of which the flag member 119 is adjusted on the tape 96. It is as desirable here as with the preferred form of con-

struction that the tubing 45 be pre-stressed before the actual bending takes place. Accordingly, the flag member 119 is adjusted in spaced relation to the sensing finger or arm 118.

It will be noted in Figures 19 and 20, that the tube gripping portion 231 of the pressure die has a tube receiving groove 233 with a serrated surface 234. The pressure die mechanism is adjusted with sufficient pressure to force the tube gripping portion tightly into contact with the tubing 45 to be bent.

As the bending die rotates, the tape 96 moving on the control drum 82 and the idler drum 95 draws the flag member 119 away from the tracer finger 118 thereby effecting an actuation of the cylinder 225 in the same manner as the pusher cylinders previously described. The piston is actuated so long as there is no deflection by finger 118. Should the flag member slow down or stop, the deflection of the sensing arm 118 by abutment against the flag member would result in a similar slowing down or stopping of the cylinders.

As the piston 226 is actuated to the rear end of the cylinder 225 it draws with it the cross-head 228 which in turn actuates the pressure die 229. The serrations 234 in the tubing groove, grip the tubing 45 and push it toward the bending die in much the same manner and for the same purposes as described in detail with the preferred form of construction.

Figure 21 illustrates another modified form of control mechanism. In this form the bending die 33 and the clamping die 44 cooperate to draw the tubing around the rounded nose of the bending die to form a bend in the tubing. As previously described with the preferred form of construction, the control drum 82 and the idler drum 95 carry an endless tape 96. Also, pusher cylinders 85 and 86 provide the pushing pressure through a cross-head 235 to force the tubing toward a cross-head 228 during the bending operation. The tracer or follower valve 117 is carried on one end of the cross-bar to position the finger 118 in line with the travel of the flag member 119.

A departure from the previously described mechanism is in the drive of a second tape 236 carrying the adjustable flag member 119. The idler drum 95 has a sprocket 237 which is operatively connected to a double sprocket 238 of a speed control device 239 by means of a driving chain 240. It is to be understood that it is within the scope of this modified invention that drums and belts may be substituted for the described sprockets and chains. Another chain or belt 241 operatively connects the sprocket 238 and a sprocket 242. The speed control device is of well known construction so that details thereof are not shown or described. The relative speed of the drums or sprockets 238 and 242 may be varied as desired through an adjusting wheel 243. The tape 236, on which the flag member 119 is adjustably carried, operatively connects the drum 242 and a drum 244.

During the bending cycle the directions of movement of the various driving belts or chains are shown by arrows. When the flag member pulls away from the tracer finger 118 the tube pushing mechanism is made operative in the same manner as previously described. Through the adjustable speed control 239, the speed of the belt or tape 236 may be varied to be greater or less than the rate at which the bend is formed. By this feature, an additional control is provided for determining the amount of metal made available at the tangent working area 79. It follows from what was said previously herein that the thickness of the tubing walls at the bend, particularly the outside wall thereof, may be controlled to the extent that the final thickness is equal to or less than the original tubing wall thickness.

Not only do the mechanisms described herein effect a control of the wall thickness in the bend of a tubing but also eliminate practically all of the strains and stresses normally incident in the usual draw-bending operations. In consequence, lighter parts may be provided thereby

effecting a reduction in the manufacturing cost and increasing the life of the machine.

The bending control mechanisms previously described are operated in such a manner as to apply a pushing pressure on the tubing as it is being bent. This is for the particular purpose of controlling or eliminating any tension and resulting stretching in the outer wall of the bend. As described, such an operation effects an increase in compression in the inner wall of the bend. However, in many bending operations of tubing, the compression in the inner wall results in wrinkling. This wrinkling usually is avoided by providing a wiper die to engage the side of the tubing along which the inside wall of the bend is formed. The wiper die has a long, forward lip extending along the tubing with its end positioned immediately adjacent the tangent of the curved nose of the bending die or its line of contact with the tubing. The support so provided permits a thickening of the inside wall at the bend without any wrinkling.

While the bend so described is structurally satisfactory, the difficulty of manufacturing and maintaining the wiper die makes the operation expensive. This excessive cost may be avoided where a bend is to be provided in which the radius is sufficient to effect a maximum amount of inside wall thickening without any wrinkling. During the bending operation it is desired that the normal travel A—B of the tubing (see Figure 17) be reduced to the point where the compression in the inside wall no longer forms wrinkling. This is accomplished by reversing or swinging the clamp structure 97 through an arc of 180°. The wedge-shaped clamp member 112 is then operated in a direction toward the bending die. If desired, a collet type chuck may be substituted for the wedge clamp member. The pusher cylinders 85 and 86 are connected to the clamp structure in a manner as previously shown. The power strokes of the pistons will continue toward the bending die but at a reduced rate controlled by the speed of movement of the flag member away from the tracer valve.

The above described modifications have not separately been illustrated as they are simple mechanical changes.

This operation eliminates the need for any wiper die. As a result, the bending mechanism is a much more simple and inexpensive construction and the bends accomplished thereby are smooth and unwrinkled.

From the foregoing description, it is believed that the nature of the several forms of the invention and the manner in which each is carried out will readily be apparent to those skilled in this art. It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a tube bending machine, a rotatable bending die, a gripping means adapted to grip tubing to the die and turn with the die, a pressure die mechanism supporting tubing against pressure developed at the point of bending, a mandrel preventing the collapse of the tubing at said point of bending, valve means having a fluid control valve operable for the control of fluid flow therethrough, a clamp construction movable toward and away from said bending die and having a wedging member for gripping tubing in the clamp construction, a first cylinder and piston means responsive to said valve means for actuating said wedging member to grip the tubing, a tracer valve having a fluid control valve in normally operative position for the passage of fluid therethrough and an arm for shifting said control valve to inoperative position, a carrier drum rotatable with said bending die, an idler drum, a belt around said drums and movable therewith at a predetermined speed relative to the rotation of said bending die, an actuator adjustable along said belt and movable in the same path of movement as and ahead of said tracer

valve, and a second power cylinder and piston means normally responsive to the fluid control valve for moving said clamp construction and clamped tubing relative to the bending die as it rotates.

5. In a tube bending machine, a rotatable bending die, a gripping means adapted to grip tubing to the die and turn with the die, a pressure die mechanism supporting tubing against pressure developed at the point of bending, a mandrel preventing the collapse of the tubing at said point of bending, a fluid valve having a spool shiftable to forward, closed and reverse positions for controlling the flow of fluid therethrough, a movable clamp construction having a wedging member for clamping tubing therein, a clamp cylinder and pistons means responsive to said fluid valve for actuating the wedging member into and out of clamping positions, a tracer valve movable with said clamp construction and having a spool shiftable to closed and reverse positions, a coiled spring normally maintaining the spool in a valve operative position for the flow of fluid through the valve, and an actuating arm movable for shifting said spool against the coiled spring to the valve closed and reverse positions, actuating means operatively connected to said bending die for co-movement therewith and movable along the path of movement of the tracer valve actuating arm, and power cylinder and piston means responsive to said tracer valve for moving said clamp construction.
10. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.
15. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means controlling the actuation of the hydraulic means and carried by the tube engaging and feeding means, a control member for said valve means, disposed in advance thereof and engageable with the valve means to render it inoperative and means actuated by the rotatable bending die for moving said control member in advance of the tube engaging and feeding means as the rotatable bending die is rotated so that the valve means is operative to permit the hydraulically operated means to advance the tube engaging and feeding means for feeding the tube toward the rotatable bending die in accordance with the rate of rotation of such die.
20. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube
25. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube
30. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.
35. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.
40. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means controlling the actuation of the hydraulic means and carried by the tube engaging and feeding means, a control member for said valve means, disposed in advance thereof and engageable with the valve means to render it inoperative and means actuated by the rotatable bending die for moving said control member in advance of the tube engaging and feeding means as the rotatable bending die is rotated so that the valve means is operative to permit the hydraulically operated means to advance the tube engaging and feeding means for feeding the tube toward the rotatable bending die in accordance with the rate of rotation of such die.
45. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.
50. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means controlling the actuation of the hydraulic means and carried by the tube engaging and feeding means, a control member for said valve means, disposed in advance thereof and engageable with the valve means to render it inoperative and means actuated by the rotatable bending die for moving said control member in advance of the tube engaging and feeding means as the rotatable bending die is rotated so that the valve means is operative to permit the hydraulically operated means to advance the tube engaging and feeding means for feeding the tube toward the rotatable bending die in accordance with the rate of rotation of such die.
55. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.
60. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means controlling the actuation of the hydraulic means and carried by the tube engaging and feeding means, a control member for said valve means, disposed in advance thereof and engageable with the valve means to render it inoperative and means actuated by the rotatable bending die for moving said control member in advance of the tube engaging and feeding means as the rotatable bending die is rotated so that the valve means is operative to permit the hydraulically operated means to advance the tube engaging and feeding means for feeding the tube toward the rotatable bending die in accordance with the rate of rotation of such die.
65. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.
70. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means controlling the actuation of the hydraulic means and carried by the tube engaging and feeding means, a control member for said valve means, disposed in advance thereof and engageable with the valve means to render it inoperative and means actuated by the rotatable bending die for moving said control member in advance of the tube engaging and feeding means as the rotatable bending die is rotated so that the valve means is operative to permit the hydraulically operated means to advance the tube engaging and feeding means for feeding the tube toward the rotatable bending die in accordance with the rate of rotation of such die.
75. In a tube bending machine, a rotatable bending die, a gripping means adapted to grip tubing to the die and turn with the die, a pressure die mechanism supporting tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, hydraulically operated means operating the tube engaging and feeding means, valve means for said hydraulically operated means carried by the tube engaging and feeding means, a control arm for said valve means and means actuated by the rotatable bending die for moving the control arm as the bending die rotates so that the control arm means is actuated in accordance with the speed of rotation of the die.

to positively feed it axially toward the bending die, power operated means for moving the tube engaging and feeding means toward the rotatable bending die, control means controlling the operation of said power operated means and carried by the tube engaging and feeding means, a control member for said control means disposed in advance of the path of movement thereof toward the rotatable bending die and engageable therewith to render it inoperative and means actuated by the rotatable bending die for moving said control member away from and in advance of the control means as the rotatable bending die is rotated so that the control means is operative to operate the power operated means for feeding the tube toward the rotatable bending die in accordance with the rate of rotation of the rotatable bending die.

6. In a tube bending machine, a rotatable bending die, means rotating said die, a tube gripping means adapted to grip tubing to the die and turn with the die, a pressure die mechanism supporting the tubing against pressure developed at the point of bending, a mandrel adapted to be positioned axially within the tube to prevent the collapse of the tube at the point of bending, a tube engaging and feeding means movable axially of the tube, said means securely engaging the tube to positively feed it axially toward the bending die, a hydraulic cylinder means having a piston means, means connecting said piston means to the tube engaging and feeding means for moving the same toward and away from the bending die, valve means controlling the communication of the cylinder means with a source of fluid pressure, said valve means being carried by the tube engaging and feeding means, a drum rotated by the rotatable die and disposed coaxially therewith, an idler pulley fixedly located relative to the drum along the axial path of movement of the

tube, an endless flexible member entrained over the drum and pulley, a control arm adjustably carried by said flexible member and disposed in advance of the tube engaging and feeding means and engageable with the valve means to hold it in a neutral, inoperative position, said valve including means operable upon the disengagement of the control arm therefrom to actuate the valve to establish communication between the cylinder means and the source of fluid pressure.

10 7. A tube bending machine as claimed in claim 6, wherein said tube engaging and feeding means includes a clamp construction and hydraulically actuated means operating said clamp construction.

15 8. A tube bending machine as claimed in claim 6, wherein said tube engaging and feeding means includes a wedging means, cylinder and piston means actuating the wedging means and valve means controlling the cylinder and piston means.
